PROCESS FOR THE DUPLICATION OF SOUND RECORDING TAPES

Hugo Westerkamp, Cologne-Braunsfeld, Germany; vested in the Alien Property Custodian

Application June 1, 1939, Serial No. 276,927
In Germany June 14, 1938

11 Claims. (Cl. 18—48.5)

The invention relates to a process for the duplication of sound tapes with mechanical sound recording by a master matrix of tape form.

Sound tapes with mechanical sound recording are generally produced by cutting sound grooves in a thin uniform layer of wax on a carrier of tape form. For the production of duplicates from such an original sound tape, a master matrix is prepared therefrom, for example by electroplating, which may be employed as a master stamping matrix. However, considerable difficulties are encountered in pressing copies from the master matrix owing to its tape form.

In contradistinction thereto, it is proposed in accordance with the invention to spray or squirt onto the surface of the master matrix provided with the sound tracks, a mass, for example a sprayable mass having a cellulose base or an artificial resin mass, capable of being sprayed or squirted in such a thin layer that a flexible coating is formed which, when detached from the master matrix, may be directly employed as a sound tape.

It is to be noted that the use of the spraying or squirting process has already been proposed for the duplication of sound discs. However, whereas in such cases it is a question of the duplication of objects of relatively small dimensions which are more or less rigid in the finished state, a sound tape is an object which is generally several metres long and must be extremely flexible in the finished state in order that it may be wound up into a roll. By reason of these differences, the idea of employing the spraying or squirting process also in the duplication of sound tapes has not been conceived, and it has actually never been proposed to duplicate sound tapes by the spraying or squirting process, although proposals for the simple and cheap production of copies of sound tapes have certainly not been lacking.

The process according to the invention is preferably carried out by winding up the master matrix into a roll with the interposition of spacing members, and filling the space between the individual turns of the roll with a sprayed or squirted mass; to this end, the spacing members are given such dimensions that the space formed thereby between the turns of the master matrix is equal to the thickness of the flexible sound tape to be produced.

For the production of endless crossed sound tapes (i. e., including a twist through 180°)

degrees about a longitudinal axis) provided with sound tracks on both sides, and which are played by successive use of grooves at opposite sides, it is proposed in accordance with the invention to cut the master matrix into two halves, to wind up these halves into a roll with the interposition of spacing members, with the sound tracks facing one another and extending in the same direction, and to fill the space between the two halves of the master matrix with sprayed or squirted material, the free ends of the sound tape provided with sound tracks on both sides which is thus produced and then being connected together in crossed fashion.

15 As tape losses may occur at the cutting and connecting point of the master matrix tape and of the copy to be produced, it is proposed in accordance with the invention, in order to allow for these losses, to prepare from the original sound

20 tape two master matrices, each of which is cut into two unequal halves, the cutting points of one master matrix lying symmetrically with respect to the cutting points of the other master matrix. The two larger master matrix halves, with the sound tracks facing one another and extending in the same direction, are then wound up into a roll with the interposition of spacing members and the space between the two master matrix halves is filled with sprayed or squirted material, whereupon the free ends of the tape provided on both sides with sound tracks which is thus produced are trimmed and connected together in crossed fashion.

25 According to the invention, sound tapes recorded on both sides may also be produced by sticking together two sprayed or squirted sound tapes with the backs facing one another, if necessary after the backs of the tapes have been flattened.

30 40 The spacing members are, according to the invention, so dimensioned and arranged that they only lie on the unrecorded edge of the master matrix, it being advisable to secure them in guides (strip-like elevations, grooves or the like) provided along the edges of the tape form master matrix.

45 45 The process according to the invention is illustrated in two working examples in the drawing.

50 Figure 1 is a sectional view of a part of a master matrix formed into a spiral roll, in a radial plane through the roll.

Figure 2 is a section substantially on line 2—2 of Fig. 1.

55 Figures 3, 4 and 5 are diagrammatic views,

showing the manner of cutting and positioning the matrix parts preliminary to forming the roll.

Figure 6 is a view corresponding to Fig. 1 and showing a modified form of roll.

Figure 7 is a sectional view substantially on line 7-7 of Fig. 6.

Figure 8 is a view showing a fragment of a sound tape.

Figure 8a is a section of the same substantially on line 8a-8a of Fig. 8.

Figure 9 is a perspective view of a sound tape formed by joining two sound tapes back-to-back.

Figure 10 is a view showing a portion of a matrix with a spacer strip having spacer blocks attached thereto.

Figures 1 and 2 relate to the duplication of sound tapes having recording on one side. A master matrix of tape form is produced from an original sound tape having a recording on one side, for example by electroplating. This master matrix, which is designated by 1 in the drawing, has on its surface, instead of the sound grooves of the original sound tape, corresponding elevations 2. The master matrix is, as is shown in Figure 1, wound up into a roll with the interposition of spacing members 3. The spacing members are only of short length and are of such width that they only lie on the unrecorded edges of the master matrix. The height of the spacing members is equal to the thickness of the sound tape to be produced. In order that the spacing members may not be displaced, the master matrix is provided at its edges with strip-like elevations 4, which engage in corresponding recesses in the spacing members and in this way hold the spacing members in position. When the master matrix is completely wound up, the spaces 5 are filled with material by the spraying or squirting operation.

The duplication of sound tapes recorded on both sides and adapted to be connected in crossed fashion is shown in Figures 3-7. A master matrix of tape form is again produced from an original sound tape continuously recorded on one side. This master matrix, which is designated by 6, is cut into two halves 6a and 6b as is shown in Figure 3, and these two halves are disposed one upon the other with the sound tracks facing each other and extending in the same direction with the leading ends of the halves adjacent one another, that is to say, the master matrix half 6a, the ends of which are designated by a and b, is placed in juxtaposition to the master matrix half 6b, the ends of which are designated by c and d, as is shown in Figures 3 and 4, and then laid over the master matrix half 6b by a hinging movement, so that the edge a¹ of the master matrix half 6a coincides with the edge a⁴ of the master matrix half 6b and the edge a² of the master matrix 6a coincides with the edge a³ of the master matrix half 6b, as is shown in Figure 5.

Between the two master matrix halves 6a and 6b, spacing members 7 are disposed, which correspond to the spacing members 3 in Figures 1 and 2, whereupon the double master matrix layer shown in Figure 5 is wound up into a roll as shown in Figures 6 and 7. When the master matrix has been rolled up, the space 8 between the double layers 6a, 6b is filled with material. The sound tape thus produced with sound tracks on both sides is then connected at its ends in crossed fashion.

In order to avoid cutting losses, it is advisable

to prepare from the original sound tape two master matrices which are each cut into two unequal halves, the cutting points of one master matrix lying symmetrically with respect to the cutting points of the other master matrix, while the two larger master matrix halves are wound up into a roll with the interposition of spacing members, with the sound tracks facing one another and extending in the same direction, and the space between the two master matrix halves is filled with material by the spraying or squirting operation.

A section of a sound tape produced in accordance with the invention as described in the foregoing and having sound tracks on both sides is shown in Figures 8 and 8a. The sound tape consists completely of the sprayed or squirted material and has the sound grooves 9 on both sides. The recesses 10 are due to the spacing members 7. The grooves 11 correspond to the strip-like elevations provided on the edge of the master matrix for the purpose of holding the spacing members in position.

Sound tapes having sound tracks on both sides may also be produced by preparing two sound tapes recorded on one side as shown in Figures 1 and 2, and connecting them together back to back, for example by adhesion, as is shown in Figure 9.

The invention is not limited to the constructional examples shown and illustrated, but numerous modifications may be made without departing from the invention. Thus, for example, as in Figure 10, instead of employing separate spacing members, a strip 20 provided with projections 21 serving as spacing members may be employed, the connecting cross pieces 22 of which for the spacing members lie outside the master matrix roll. The original sound tape and the master matrix may also be made wider than is necessary at the outset and the sound tape consisting of sprayed or squirted material which is produced in accordance with the invention may be cut at the edges so as to eliminate the recesses 10 caused by the spacing members, in which case a further guide groove may be provided on both sides of the sound track.

I claim:

1. A process for the duplication of sound tapes through mechanical sound recording upon an original sound record tape, which comprises preparing from the original sound record tape a master matrix of uniform width having upon its surface multiple parallel ribs corresponding to the sound tracks, spraying or squirting a substance selected from the group consisting of moldable artificial resin and cellulose plastics onto the surface of the master matrix and therewith forming a thin continuous layer on substantially the entire area thereof, and stripping the layer from the master matrix as a flexible duplicate sound tape having a plurality of parallel sound tracks corresponding to the sound tracks of the original record tape and being substantially of the same area as the matrix.

2. A process for the duplication of sound tapes through mechanical sound recording upon an original sound record tape, which comprises preparing a master matrix from the original sound record tape, winding the master matrix into a spiral with its successive convolutions spaced apart, spraying or squirting a mass selected from the group consisting of moldable artificial resin and cellulose plastics into the spiral space be-

tween the convolutions of the master matrix to fill said space and thereby form a thin continuous spiral layer, and stripping the layer from the master matrix as a flexible duplicate sound tape having sound tracks corresponding to the sound tracks of the original record tape.

3. A process for the duplication of sound tapes through mechanical sound recording upon an original sound record tape, which comprises preparing a master matrix from the original sound record tape, cutting the master matrix transversely to form halves, placing the halves back-to-back and winding them into a spiral with the sound tracks facing one another and extending in the same direction, the sound track faces of the halves being spaced apart to provide a spiral space, spraying or squirting a mass selected from the group consisting of moldable artificial resin and cellulose plastics into the spiral space between the successive convolutions of the master matrix to fill said space and thereby form a thin continuous spiral layer, and stripping the layer from the master matrix as a flexible duplicate sound tape having sound tracks corresponding to the sound tracks of the original record tape.

4. A process for the duplication of sound tapes through mechanical sound recording upon an original sound record tape, which comprises preparing two master matrices from the original sound record tape, cutting each master matrix transversely at a point near its center of length, the point of cutting one master matrix being symmetrical with respect to the cutting point of the other master matrix about an axis constituted by the mid-length of either master matrix, placing the longer portions of the master matrices back-to-back and winding them into a spiral with the sound tracks facing one another and extending in the same direction, the sound track faces of the halves being spaced apart, spraying or squirting a mass selected from the group consisting of moldable artificial resin and cellulose plastics into the space between the successive convolutions of the master matrix to fill said space and thereby form a thin continuous spiral layer, and stripping the layer from the master matrix as a flexible duplicate sound tape having sound tracks corresponding to the sound tracks of the original record tape.

5. A process for the duplication of sound tapes, through mechanical sound recording of sound lines upon an original sound record tape, which comprises preparing a master matrix from the original sound record tape, said master matrix having a width greater than that of the duplicate sound tape to be made, winding the master matrix into a spiral with its surfaces spaced apart, spraying or squirting a mass selected from the group consisting of moldable artificial resin and cellulose plastics into the space between the convolutions of the master matrix to fill said space, and stripping the layer from the master matrix as a flexible duplicate sound tape having sound tracks corresponding to the sound tracks of the original record tape, and trimming edge portions from said layer and thereby forming the flexible duplicate sound tape.

6. A process for the duplication of sound tapes through mechanical sound recording upon an original sound record tape, which comprises preparing a master matrix from the original sound record tape, said master matrix having a width greater than that of the duplicate sound tape to be made and having elevated portions at its edges, winding the master matrix into a spiral

5 with its surfaces spaced apart, said surfaces being maintained in spaced position by spacing members held in position by engagement with said elevations, spraying or squirting a mass selected from the group consisting of moldable artificial resin and cellulose plastics into the space between the convolutions of the master matrix to fill said space, stripping the layer from the master matrix as a flexible duplicate sound tape having sound tracks corresponding to the sound tracks of the original record tape, and cutting edge portions from said layer to form the flexible duplicate sound tape.

7. A mold for forming duplicate sound record tapes through mechanical sound recording on an original sound record tape and by means of a master matrix prepared from said original record tape, comprising a spiral coil formed by winding the master matrix with successive convolutions spaced apart, and spacing means including blocks of limited dimensions located at the edges of the master matrix and between successive convolutions thereof, the sound track area of the master matrix being free of the blocks and the blocks being spaced apart along the length of the master matrix for permitting tape-forming material to be sprayed or squirted into the space between the convolutions for filling the same.

8. A mold for forming duplicate sound record tapes through mechanical sound recording on an original sound record tape and by means of a master matrix prepared from said original record tape, comprising a spiral coil formed by cutting the master matrix transversely to form halves and winding the halves in back-to-back position with successive convolutions spaced apart, and spacing means including blocks of limited dimensions located at the edges of the master matrix and between successive convolutions thereof, the sound track area of the master matrix being free of the blocks and the blocks being spaced apart along the length of the master matrix for permitting tape-forming material to be sprayed or squirted into the space between the convolutions for filling the same.

9. A mold for forming duplicate sound record tapes through mechanical sound recording on an original sound record tape and by means of two identical master matrices prepared from said original record tape, comprising a spiral coil formed by cutting the master matrices transversely at lines symmetrical with respect to the mid-length thereof and winding the longer sections in back-to-back position with successive convolutions spaced apart, and spacing means including blocks of limited dimensions located at the edges of the master matrix and between successive convolutions thereof, the sound track area of the master matrix being free of the blocks and the blocks being spaced apart along the length of the master matrix for permitting tape-forming material to be sprayed or squirted into the space between the convolutions for filling the same.

10. A process for the duplication of sound tapes through mechanical sound recording upon an original sound record tape, which comprises preparing from the original sound record tape a master matrix having upon its surface multiple parallel ribs corresponding to the sound tracks, arranging parts of the master matrix opposite one another to provide a narrow space therebetween, said ribs extending into said space at both sides thereof, spraying or squirting a substance selected from the group consisting of

moldable artificial resin and cellulose plastics into said space and therewith forming a thin continuous layer having reproductions upon its opposite surfaces of said parts of the matrix, and stripping the layer from the parts of the master matrix as a flexible duplicate sound tape having a plurality of sound tracks corresponding to the sound tracks of the original record tape and having substantially the same area as the matrix.

11. A process for the duplication of sound tapes through mechanical sound recording upon an original sound record tape, which comprises preparing from the original sound record tape a master matrix having upon its surface multiple

parallel ribs corresponding to the sound tracks, employing the master matrix to provide a wall of a mold having a narrow space into which the ribs project, spraying or squirting a substance selected from the group consisting of moldable artificial resin and cellulose plastics into said space and therewith forming a thin continuous layer having upon its surface the reproduction of said matrix, and stripping the layer from the master matrix as a flexible duplicate sound tape having a plurality of sound tracks corresponding to the sound tracks of the original record tape and substantially the same area as the matrix.

HUGO WESTERKAMP.
